(57) **CLAIM**

The ornamental design for a space capsule, as shown and described.

DESCRIPTION

FIG. 1 is a perspective view of a space capsule showing our new design;

FIG. 2 is a right side view thereof;

FIG. 3 is a left side view thereof;

FIG. 4 is a front view, the rear view being identical;

FIG. 5 is a top view thereof;

FIG. 6 is a bottom view thereof;

FIG. 7 is a right side view of a space capsule showing an alternate embodiment of our new design;

FIG. 8 is a left side view thereof;

FIG. 9 is a rear view thereof, the front view of the alternate embodiment being identical to FIG. 4; and,

FIG. 10 is a bottom view thereof, the top view of the alternate embodiment being identical to FIG. 5.

Some of the broken lines in the figures are included for the purpose of illustrating portions of the space capsule, and others are included for the purpose of showing environment and any of the broken lines form part of the claimed design.
